I. GISSER.
EXPANSION BOLT,
APPLICATION FILED JUNE 2, 1916.

1,198,719.

Patented Sept. 19, 1916.

Inventor
ISIDOR GISSER

By his Attorney

Albert Bersin.

UNITED STATES PATENT OFFICE.

ISIDOR GISSER, OF NEW YORK, N. Y., ASSIGNOR OF ONE-HALF TO MEYER GORIN, OF BROOKLYN, NEW YORK.

EXPANSION-BOLT.

1,198,719.

Specification of Letters Patent. Patented Sept. 19, 1916.

Application filed June 2, 1916. Serial No. 101,213.

To all whom it may concern:

Be it known that I, ISIDOR GISSER, a subject of the Czar of Russia, and a resident of New York, in the county of New York, 5 State of New York, have invented certain new and useful Improvements in Expansion-Bolts, of which the following is a specification.

This invention relates to that class of expansion bolts in which a split sleeve and a nut having a tapering outer surface are used in connection with a bolt which is adapted to be screwed into the tapering nut, causing the latter to move into the split sleeve and 15 thereby separate the two parts of the sleeve.

The object of this invention is to provide a comparatively simple and inexpensive device, with but few parts and which, when assembled together, will not become separated and lost during shipment.

One of the important features of my device is that at the side of one of the segments of the outer sleeve, a curved socket is provided into which a curved lug projecting 25 from the side of the second segment is adapted to fit, providing thereby a swinging joint. The above joint is placed near the top of the split sleeve permitting thereby a considerable amount of expansion of the 30 sleeve without binding on the bolt inserted inside of it. The two segments are held together by means of any of the three alternate methods shown, each one of which will keep the two segments of the sleeve permanently locked after the expansion bolt is 35 inserted into the prepared hole in wood or masonry.

Other novel features of my device will be apparent from the detailed description and 40 the accompanying drawing forming a part of this specification in which like numerals designate similar parts in all the views and in which:—

Figure 1 is a side view of an assembled 45 expansion bolt placed inside of a prepared hole in wood or masonry. Fig. 2 is a longitudinal section of one of the segments of the split sleeve and taken on line 2—2 of Fig. 5. Fig. 3 is a longitudinal section of 50 the second segment of the split sleeve and taken on line 3—3 of Fig. 6. Fig. 4 is a cross section of the bolt taken on line 4—4 of Fig. 1. Fig. 5 is an end view of one of the segments of the split sleeve looking in 55 the direction of line 5—5 of Fig. 2. Fig. 6

is a cross section on line 6—6 of Fig. 3. Fig. 7 is a partial side view of two segments of a split sleeve showing an alternate method of locking the segments together. Fig. 8 is a cross section taken on line 8—8 of Fig. 7. 60 Fig. 9 is a partial side view of two segments of a split sleeve showing another alternate method of locking the segments together. Fig. 10 is an end view of the sleeve shown in Fig. 9. Fig. 11 is a side view of the 65 tapering nut. Fig. 12 is a top view of the tapering nut. Fig. 13 is a cross section taken on line 13—13 of Fig. 1.

Referring to the drawings, the two segments 1 and 2, together forming a split 70 cylindrical sleeve and preferably made of malleable iron have their outer surface formed into a connected series of truncated cones, or roughened in any other suitable manner, thereby preventing the withdrawal 75 of the bolt from the hole after the sleeve has expanded. The two segments of the sleeve are cut away as shown forming two intervening tapering slots 3 adapted to receive the projecting lugs 5 on the tapering nut 4. 80 The two curved sockets 6 provided near the top of the sides of the segment 1, are adapted to receive the mating curved lugs 7 projecting from the sides of the segment 2. The metal bands 8 preferably cast integrally 85 with the segment 1 are bent around the segment 2 until they fit snugly into the groove 10 at the top of the latter, while the hook ends 9 of the bands 8 engage with the radial slot 11 in the segment 2 as is clearly shown in Fig. 4. The groove 10 is made wider than the strap 8 and is inclined as is clearly 90 shown in Fig. 1 in order to permit the expansion of the sleeve. The tapering nut 4 is inserted between the two segments 1 and 2 of the sleeve. The bolt 12 is screwed into the nut 4 while the latter is prevented from 95 rotating by means of the lugs 5 engaging with the sides of the tapering slots 3.

Referring to Fig. 1 it will now be evident 100 that if the assembled expansion bolt be inserted into a hole 13, and the bolt 12 turned, the head of the bolt will bear against the surface of the plate 14 while the tapering nut 4 will be moved upwardly. The outer surface of the nut 4 by bearing against the inclined inner surfaces of the segments 1 and 2 of the split sleeve, will cause the latter to expand, while the curved lug 7 will rotate in the curved socket 6. After the split 110

sleeve has expanded, the bolt will be securely locked in place.

A modified method of locking the two segments of the split sleeve together is shown in Figs. 7 and 8. The segments 15 and 16 of a split sleeve are similar to the segments 1 and 2 respectively except that instead of having the bands 8 cast integrally with the segment 1, the segment 15 is provided with a groove 17 while the segment 16 is provided with a similar groove 17 and a slot 19 similar to slot 4 in segment 2. A flexible metal band 18 provided with hook ends 20 is adapted to fit into the groove 17 in the segments 15 and 16 while the hook ends 20 engage with the slot 19 thereby holding the segments 15 and 16 together.

Another method of holding the segments of the split sleeve together is shown in Figs. 9 and 10. The segments 21 and 22 are similar to the segments 1 and 2 except that instead of using a band to hold the segments together, the segment 22 is provided with pins 23 which engage with corresponding holes in the segment 21, thereby forming a pivoted joint as is clearly shown in Fig. 10.

Having thus described my invention, I claim as new and wish to secure by Letters Patent:

1. An expansion bolt comprising, a split sleeve having a radial slot near its top, one of the segments of said sleeve having a curved socket near its top, the other segment of said sleeve having a curved projecting lug

adapted to fit into the socket of the first segment, means for keeping said lug and socket in engagement but permitting relative motion of the two, comprising a band having hook ends adapted to envelop said sleeve while said hook ends engage with said radial slot, a tapering nut fitting inside of said sleeve, means for locking said nut against rotation relative to the sleeve, and a bolt fitting inside of said sleeve and engaging with said nut, whereby the sleeve is expanded when the tapering nut is pulled into said sleeve.

2. An expansion bolt comprising; a split sleeve, one of the segments of said sleeve having an annular groove near its top and a radial slot within said groove, means for holding the two segments of the sleeve together comprising two bands having hook ends and cast integrally with the second segment of the sleeve adapted to be bent over until the said bands fit into the annular groove in the first segment and the hook ends engage with the radial slot therein, a tapering nut fitting inside of said sleeve, means for locking said nut against rotation relative to the sleeve, and a bolt fitting inside of said sleeve and engaging with said nut, whereby the sleeve is expanded when the tapering nut is pulled into said sleeve.

Signed at Brooklyn, county of Kings, 65 State of New York, this 31st day of May, 1916.

ISIDOR GISSEK.
